(57) **CLAIM**

The ornamental design for a smart watch, as shown and described.

DESCRIPTION

FIG. 1 is a first perspective view of a smart watch showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view of the smart watch thereof; and,
FIG. 10 is an enlarged view of the selected portion 10 in
FIG. 1.

The broken lines shown in the drawings depict portions of the smart watch that form no part of the claimed design. The dash dot dash broken lines in FIGS. 1 and 10 are included to show a partially enlarged view only and form no part of the claimed design.

1 Claim, 10 Drawing Sheets
